UNITED STATES PATENT OFFICE.

ORION K. TILLMAN, OF HORNERS, WEST VIRGINIA.

REEL FOR BARBED WIRES.

1,249,691.

Specification of Letters Patent. Patented Dec. 11, 1917.

Application filed June 8, 1917. Serial No. 173,590.

To all whom it may concern:

Be it known that I, ORION K. TILLMAN, a citizen of the United States, residing at Horners, in the county of Lewis and State 5 of West Virginia, have invented certain new and useful Improvements in Reels for Barbed Wires, of which the following is a specification.

My invention is a reel for supporting 10 barbed wire, during the application of the wire to a fence, the object of the invention being to provide a reel which may be readily carried by two workmen without liability of the barbs coming in contact with the 15 hands or other parts of the body and which may be readily carried between trees or other objects. A further object of the invention is to provide a construction which will permit a reel to be quickly inserted and 20 an empty reel or spool to be removed. Other incidental objects of the invention will appear as the description of the same proceeds.

In the drawings,

25 Figure 1 is a perspective view of a barbed wire reel constructed in accordance with my invention;

Fig. 2 is an end view of the same;

Fig. 3 is a longitudinal section through 30 the reel;

Fig. 4 is an enlarged end view of the reel showing the base or guard frame disposed so as to permit the reel to be easily carried through a narrow space;

35 Fig. 5 is a view showing the manner of mounting a metal reel in the frame.

In carrying out my invention, I employ a pair of standards 1 which may be constructed of any suitable material and will 40 preferably be connected at their upper ends by a beam 2, the standards and the beam forming an inverted U-shaped frame. Across the top and partway down the sides of the U-shaped frame thus produced, I 45 secure a reinforcing and bracing bar 3 of metal having laterally extending handles 4 at its ends, as clearly shown. In the standards, near the lower ends thereof, I provide openings which receive a removable axle or 50 supporting rod 5 having a head 6 or other form of stop at one end and equipped at its other end with a nut 7 adapted to be turned home against the adjacent standard so that the rod or axle may be securely fastened in the standards. The reel will be 55 mounted to rotate upon this axle or support-

ing rod between the standards and spacing sleeves or collars 8 will be fitted upon the axle between the respective standards and the adjacent ends of the reel so that movement of the reel longitudinally of the axle will be prevented and the reel thus maintained equidistant from the two sides of the supporting frame so that the workmen carrying the device will not be unduly exposed 60 to injury from the barbs. The lower extremities of the standards 1 are rabbeted or provided with depending flanges 9 which are adapted to fit against the inner faces of the side bars 10 of a base or guard frame 70 which is completed by cross bars 11 secured to and extending between the ends of the side bars 10. The standards are pivotally connected with this base or guard frame by brackets or connecting plates 12 which are 75 L-shaped or of a right angular formation having one arm rigidly secured to the side bar of the guard frame and the other arm pivotally attached to the outer side of the adjacent standard. The pivot pin or bolt 13 is 80 located at or near one vertical edge of the standard, and this point is nearer one end of the guard frame than the other end thereof, the result being that the guard frame will be overbalanced and will tend to swing so 85 that the upper edges of its side bars will be held against the lower ends of the standards 1.

The reel may be formed of wooden bars, as illustrated in Figs. 1, 2, 3 and 4, which is 90 the type generally employed by barbed wire manufacturers. This type of reel has central openings in its ends which will fit closely around the axle 6 so that the reel will not be apt to be distorted under the 95 strain imposed upon the wire while it is being applied to a fence and will not be apt to tilt or rock so as to entangle the wire. The barbed wire is sometimes furnished upon reels constructed of metallic rods, such a reel 100 being shown at 14 in Fig. 5. These reels have very large openings in their ends and would rock or tilt excessively upon an axle or supporting rod intended primarily for a wooden reel. I, therefore, provide a sleeve 105 15 which may be of wood and which will be of such dimensions that its bore will snugly receive the axle 16 while its ends will fit closely in the central openings in the ends of the reel. This sleeve may abut the adjacent standard at one end and be there equipped with pins 17 whereby movement of 110

the reel toward said standard will be prevented. At the opposite end of the reel, a spacing disk 18 may be fitted about the axle between the reel and the adjacent standard.

5 It is thought the use and advantages of my improved device will be readily understood from the foregoing description taken in connection with the accompanying drawings. The barbed wire will pass from the 10 reel under one end bar of the base or guard frame, as shown clearly in Fig. 1, and will be thereby so disposed that the hands or bodies of the workmen will not be apt to be scratched by the barbs as they pass from 15 the reel and the device may be easily carried by the workmen, one at either side, grasping the handles 4. Should the progress of the work bring the workmen to a point where a tree or some other object is close to the 20 fence, and the space is so contracted that ordinarily two men could not pass through it, the guard frame is swung about its pivotal connection with the standards, as shown in Fig. 4, so that it will lie close against the 25 standards, whereupon the workmen may swing the entire device around and pass through the space in single file instead of attempting to go through abreast. Should the field or line of fence be clear of trees 30 or other plants, the guard frame may be locked in its position by means of a pin 19 inserted through openings 20 and 21 in the side bars of the guard frame and the lower 35 ends of the standards or flanges 9, as will be readily understood. It will be readily

noted that the lower ends of the standards and the side members of the guard frame have an angular engagement so that they will not readily be displaced and, consequently, the guard frame will always be in position to prevent a person running against or brushing by the roll of barbed wire. The device is preferably constructed of wood, but it may be made of angle iron or any other preferred material.

Having thus described the invention, what is claimed as new is:

1. The combination of a carrier frame, an axle removably fitted in the lower ends of the frame, and a reinforcing bar secured 50 over the top and against the sides of the frame and having handles at its ends projecting laterally from the sides of the frame.

2. The combination of a supporting frame, means for mounting a reel therein, a guard frame adapted to bear against the lower ends of the supporting frame and extending in opposite directions beyond the opposite sides of the same, and connecting devices secured rigidly to the guard frame and pivotally attached to the supporting frame, the said connecting devices and pivots being located eccentric relative to the two frames whereby the guard frame will be overbalanced and will tend to extend 60 across the lower ends of the supporting frame.

In testimony whereof I affix my signature.

ORION K. TILLMAN. [L.S.]
